PREPARATION OF EMULSIFYING SOAPS

Jack Robinson, Wood River, Ill., assignor to
Standard Oil Company, Chicago, Ill., a corpo-
ration of Indiana

No Drawing. Application January 25, 1933,
Serial No. 653,477

6 Claims. (CL. 87—5)

This invention relates to the purification of sulfonic soaps and it pertains more particularly to the removal of salts from preferentially oil-soluble petroleum sulfonic soaps of the type employed in the preparation of soluble oils, detergents, wetting agents, etc.

The sulfonic soaps which are hereinafter called mahogany soaps may be prepared in the manner described by U. S. Patents 1,196,274 and 10 1,286,179, or they may be prepared by neutralizing the sulfonic acids prepared by the method of U. S. Patent 1,087,888. These mahogany soaps may be used as emulsifiers as described in U. S. Patent 1,230,599. I have found that the mahogany soaps as heretofore produced contain large amounts of sodium sulfate and other salts, and that these salts and impurities are extremely detrimental, particularly when the soaps are to be used as wetting agents, detergents, emulsifying 15 agents and the like. The object of my invention is to provide a mahogany soap which is substantially free of salts and other impurities.

A further object of the invention is to avoid the expense and trouble of using high proof 25 (70%) alcohol for the extraction of mahogany soaps from impurities. A further object is to avoid emulsion difficulties in the purification of mahogany soap and to recover the purified soap in a form which is particularly desirable for the 30 preparation of emulsifying agents, wetting agents and the like.

Prior attempts to remove sodium sulfate from mahogany soap have indicated that there is a dispersion of the sodium sulfate in the oil phase 35 from which mahogany soap is extracted, and there is some indication that the sodium sulfate forms a salt with the mahogany soap which further interferes with the separation. The sodium sulfate cannot be washed from the mahogany 40 soap solution with water chiefly because of the emulsion difficulties. I have discovered that by maintaining the concentration of electrolyte above a certain minimum value, I may effectively prevent emulsification, and furthermore, I have 45 found that sodium sulfate and mahogany soap may be readily separated by means of an alkaline solution. More specifically, I have found that when the impure mahogany soap is washed with a 3-10% solution of sodium hydroxide, there is no 50 emulsification difficulty and the sodium sulfate is readily removed. I prefer to carry out the washing step in a 10-20% solution of soap in naphtha.

The process is applicable to the mahogany soap either before or after the soap is extracted from 55 the oil in which it is first formed. For example,

I may repeatedly treat a Mid-Continent lubricating oil stock with concentrated or fuming sulfuric acid, separating and withdrawing the sludge from the treated oil. I may then neutralize the sour oil with caustic, thereby forming mahogany soap and large quantities of sodium sulfate. If I endeavor to wash out the sodium sulfate with water 5 it removes the sodium sulfate therewith.

In accordance with my invention I wash the neutralized oil with a 3-10% solution of sodium hydroxide, preferably using a number of dumps or using a countercurrent washing system. With 10 this percentage of sodium hydroxide I prevent emulsification and I also effect the separation of the sodium sulfate from the mahogany soap. After countercurrent treatment with from one-half to four volumes of the caustic solution, or 15 after one or more dumps with about one-half to two volumes of the caustic solution I may extract the mahogany soap from the oil with alcohol in accordance with well known refinery practice. The extracted mahogany soap, however, will be 20 substantially different from mahogany soap heretofore extracted because it will not contain appreciable amounts of sodium sulfate. The slight alkalinity of the finished product may be neutralized with rosin acid or a fatty acid to prepare 25 the finished emulsifying compound, wetting agent or detergent.

Instead of washing a neutralized oil prior to the extraction of the mahogany soap, I may wash the extract per se with caustic. In fact, this 30 procedure is highly desirable because it requires much smaller equipment and a smaller amount of caustic wash liquor. I prefer to use about a 5% solution of sodium hydroxide but the concentration of said solution may vary from about 35 3% to 10% or more. Here again I may use a continuous countercurrent washing system, or I may employ a plurality of separate dumps, in which case I may use the caustic which has been 40 used for removing the final traces of salt from one body of mahogany to extract further amounts of salt from a less pure mahogany soap. The mechanical features and details of my operation form no part of the present invention and 45 they will not therefore be described in detail.

I may also effect the washing with caustic solution in the presence of a light hydrocarbon diluent, such as naphtha, and the amount of this diluent may be varied within wide limits. I prefer 50 55

to use about 80-90% of naphtha in washing soap from a lubricating oil of intermediate viscosity.

When removing impurities from extracted mahogany soap I prefer to avoid the use of naphtha diluent and to effect the removal of sodium sulfate in a hot aqueous solution. The impure soap may be dissolved in hot water to form a 20-30% solution. I add to this solution, with stirring, sufficient strong sodium hydroxide to bring the concentration of the aqueous phase to 3-10%. The mixture is allowed to settle while it is hot. I have found that the use of hot water in combination with the regulation of the alkalinity of pH value makes it possible to obtain a better separation of impurities, freedom from emulsion difficulties and an improved product.

An important use of my purified mahogany soap is in the preparation of oil emulsions. An oil emulsion or a soluble oil which enjoys wide commercial use has about the following composition: about 3% soda rosin soap, about 10% mahogany soap, 1.5% water, 1.5% alcohol, and 84% light mineral oil (viscosity about 50-80 seconds at 100° F.). The presence of sodium sulfate interferes with the emulsification of the oil, and it impairs the stability of the finished emulsion. By eliminating this impurity I overcome these difficulties, and I have even discovered that the alcohol content may be reduced or even eliminated without impairing the quality or stability of the emulsion. It will be seen from the above formula that a small amount of water and of soda rosin soap is necessary. I find that this amount of water and the amount of soda for making the soap may be left in the mahogany soap when the sodium sulfate is being removed therefrom, and thus I merely have to add a little rosin acid and light mineral oil with perhaps a small amount of alcohol to prepare the finished

soluble oil composition. Another method of making soluble oils takes advantage of the diluent effect of the oil which is to be emulsified. I combine the impure mahogany soap and the mineral oil in the proportions specified in the formula. I then wash this mixture with 3-10% sodium hydroxide solution, neutralize the excess alkalinity with rosin acids, etc. and add other necessary ingredients.

The alkalinity of the washed mahogany soap may also be utilized in the preparation of detergents and wetting agents. However, if it is desired to obtain pure mahogany soap, this final

alkalinity may be neutralized with pure mahogany acid.

While I have described in detail a preferred embodiment of my invention, it should be understood that I do not limit myself to the details hereinabove set forth except as defined by the following claims which should be construed as broadly as the prior art will permit. It will be understood that the invention may be applied to the purification of other sulfonated fats and oils, such as sulfonated castor oil,—also that other alkalies such as potassium or ammonium hydroxide may be used. Other expedients will be apparent to those skilled in the art.

I claim:

1. The method of making a soluble oil from mahogany soap, which comprises washing impure mahogany soap with a 3% to 10% aqueous solution of sodium hydroxide, removing the aqueous washing solution and impurities from the slightly alkaline mahogany soap, neutralizing the alkalinity of the washed mahogany soap with a soap-forming acid, and admixing said neutral soap with a light mineral oil.

2. The method of preparing an emulsifying composition from oil soluble mineral oil sulphonic soaps which comprises washing said soaps containing sodium sulfate and other impurities with a 3% to 10% aqueous solution of alkali metal hydroxide whereby the formation of serious emulsions is avoided, separating the sulphonic soap from the aqueous layer containing sulfates and impurities, and neutralizing the alkalinity of the soap by adding a soap-forming acid thereto.

3. The method of claim 2 wherein the mahogany soap is diluted with a large amount of light mineral oil.

4. The method of claim 2 wherein the soap-forming acid is a fatty acid.

5. The method of claim 2 wherein the soap-forming acid is a rosin acid.

6. The method of making a soluble oil from impure mahogany soap which comprises adding to said soap the light mineral oil to be used in the soluble oil, washing the mixture of mineral oil and impure mahogany soap with a 3% to 10% aqueous alkali metal hydroxide solution, separating the aqueous phase and impurities from the oil phase, and neutralizing excess alkalinity in the oil phase with a soap-forming acid to form an emulsifying soap which will supplement the mahogany soap in the soluble oil.

JACK ROBINSON.
